(57) CLAIM

The ornamental design for an automatic cooker as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an automatic cooker, showing my design;

FIG. 2 is a left side view thereof;

FIG. 3 is a right side view thereof;

FIG. 4 is a top view thereof;

FIG. 5 is a rear view thereof; and,

FIG. 6 is a bottom view thereof.

The word 'GREENPAN' appears in the drawings as an ornamental feature forming part of the claimed design and is a registered trademark of Apollo Topco, a besloten vennootschap (b.v.) organized under the laws of Belgium.
